UNITED STATES PATENT OFFICE.

HUGO SACK, OF DUSSELDORF, GERMANY; ADELHEID SACK WIDOW AND HEIR OF SAID
HUGO SACK, DECEASED.

METHOD OF PRODUCING I-BEAMS.

1,013,567.

Specification of Letters Patent.

Patented Jan. 2, 1912.

Application filed November 30, 1908, Serial No. 465,410. Renewed October 4, 1909. Serial No. 520,829.

To all whom it may concern:

Be it known that I, Hugo Sack, a subject of the Emperor of Germany, residing at Dusseldorf, Rhenish Prussia, Germany, 5 have invented certain new and useful Improvements in Methods of Producing I-Beams, of which the following is a specification.

In my application for U. S. Letters Patent filed January 21, 1907, Serial Number 353,380, I have disclosed a method of producing I-beams with taperless flanges, which consists in first rolling a bar having a central web and taperless non-parallel 15 flanges, and then passing the initial bar through a universal finishing mill having rolls which bend the flanges into parallelism. In the practice of said process, it has been found that the horizontal finishing 20 rolls, which lie between and support the taperless flanges while they are being bent into final position, undergo great wear and rapidly deteriorate. This is due to the scraping action of the flanges upon the 25 vertical end walls of said rolls.

The present invention is a method of producing I-beams with broad taperless flanges, comprising three steps. A blank is first rolled into a preliminary bar having a 30 web and pairs of marginal, oppositely-disposed, non-parallel flanges, the web and flanges being substantially of the final width and thickness and the flanges being substantially taperless. This bar is then 35 passed through a set of universal rolls which bend the flanges partially toward parallelism. The intermediate product is then brought into finished form by supporting the web and applying pressure to 40 the outer sides of the flanges, in lines substantially parallel to the web, for example by passing the bar twice, in reversed position through a special set of three rolls.

Referring to the accompanying drawing:—Figure 1 is a side elevation of portions of the initial reducing rolls, showing the preliminary bar in their pass; Fig. 2 is a similar view of the rolls employed for carrying out the second step of the process; 50 and Fig. 3 is a side elevation of the finishing rolls, showing the upper flanges of the I-beam flattened down into the same plane.

The universal reduction mill A shown in Fig. 1 comprises two horizontal rolls 1 and

two vertical rolls 2, 3, the horizontal rolls 55 being identical and individually assymetrical and the vertical rolls being different but symmetrical. Each horizontal roll has a working face comprising an intermediate cylindrical surface 4 and frusto-conical 60 end-surfaces 5. Each vertical roll has a working face comprising upper and lower frusto-conical surfaces 6, 6, respectively parallel to the end-surfaces 5, 5, of the upper and lower horizontal rolls. The resulting pass is of such shape as to serve for the production of a preliminary bar 7 having a web and wide taperless flanges lying at a considerable angle to a vertical plane, such bar being shown in section in the pass. 70

In order to produce a preliminary bar without fins, each horizontal roll 1 is provided at its left-hand end with an outwardly-flaring collar 8, continuous with the end-surface 4, and the right-hand vertical 75 roll 3 is provided at its upper and lower ends with outwardly-flaring collars 9, continuous with the surfaces 5. The collars 8 shape the edges of the flanges at the left-hand of the bar, and any surplus metal is 80 extruded as fins between these collars and the roll 2. The bar is then reversed, or rotated through an angle of 180°, and is again passed through the rolls, whereupon the collars 9 of roll 3 bear on the outer corners of the flanges and suppress such fins. 85

While the described mill A is well adapted to carry out the first step of the method, the preliminary bar may be otherwise rolled, for example, by passing the blank, without rotation, successively through two universal mills each having symmetrical rolls, the rolls of the second mill being constructed to suppress any fins produced in the first mill, as disclosed in my U. S. Letters Patent No. 95 970,559, granted September 20, 1910.

The intermediate mill B shown in Fig. 2 consists of pairs of identical symmetrical horizontal rolls 10 and vertical rolls 11. The working surfaces of these rolls are 100 of the same general shape as those of the reduction-rolls of the first mill. The parallel surfaces 12, 13 of the horizontal and vertical rolls, however, are at a considerably smaller angle to a vertical plane than are 105 the corresponding surfaces of the reduction-mill. The dotted lines 15, 15 indicate the corresponding position of the side portions

of the pass of the reduction-rolls A and also indicate the position of the flanges of the preliminary bar 7 which is fed from the mill A into this mill B. As this bar enters 5 the pass of the mill B, in the second stage of the process, the surfaces 13 of the vertical rolls 11 bend the flanges 14 from the positions indicated by dotted lines into those shown in full lines, thus bringing the flanges 10 approximately into parallelism without causing them to unduly press upon and wear the working roll-surfaces.

The third and final step of the process may be effected by the mill C shown in Fig. 15 3. This mill comprises a long horizontal cylindrical roll 16 having journals at each end, and two identical short cylindrical rolls 17, each having a journal at its outer end 20 only. The rolls 17 are arranged to enter beneath and support the flanges of the bar delivered by the mill B, while the roll 16 25 presses on these flanges and bends them down from the positions indicated by the dotted lines into a single plane. By reversing the 30 bar and again passing it through these rolls C, the other flanges are also flattened down and brought into parallelism with the first pair. This third stage of the process enables the bending of the flanges to be completed 35 without unduly wearing the working surfaces of the rolls C.

Other devices, such as a press having flat opposed reciprocating platens to bear on the flanges, may be employed to execute the 35 third step of the process, in lieu of the rolls C.

The adjective "non-tapering," as used in Claim 1, means flanges which do not taper from the web to their edges, but which are

as thick at or near their edges as at points intermediate their edges and the web.

I claim:

1. The method of producing I-beams, which consists in first rolling an I-bar having a web and non-parallel non-tapering flanges of substantially the desired width and thickness, then passing said bar through a universal mill having its roll-axes in one plane and thereby forcing the flanges into approximate parallelism, and finally bending each pair of adjacent flanges into one 45 plane by supporting the blank substantially at the junction of its web and flanges and applying pressure to the outer sides of the flanges in lines substantially parallel to the web.

2. The method of producing I-beams, which consists in first rolling an I-bar having a web and non-parallel flanges of substantially the desired width and uniform thickness, then passing said bar through a 60 universal mill having its roll-axes in one plane and thereby forcing the flanges into approximate parallelism, and finally bending each pair of adjacent flanges into one 65 plane by supporting the blank substantially at the junction of its web and flanges and applying pressure to the outer sides of the flanges in line substantially parallel to the web.

In testimony whereof, I affix my signature in presence of two witnesses.

HUGO SACK.
